J. E. WALKER.

ADJUSTABLE FOOT REST FOR SHOE SHINING STANDS,
APPLICATION FILED NOV. 16, 1921.

1,424,959.

Patented Aug. 8, 1922.

UNITED STATES PATENT OFFICE.

JAMES EMORY WALKER, OF HECLA, SOUTH DAKOTA.

ADJUSTABLE FOOT REST FOR SHOE-SHINING STANDS.

1,424,959.

Specification of Letters Patent. Patented Aug. 8, 1922.

Application filed November 16, 1921. Serial No. 515,636.

To all whom it may concern:

Be it known that I, JAMES E. WALKER, a citizen of the United States, residing at Hecla, in the county of Brown and State of 5 South Dakota, have invented certain new and useful Improvements in Adjustable Foot Rests for Shoe-Shining Stands, of which the following is a specification.

This invention relates to improvements in 10 shoe shining stands and particularly to means for eliminating the risk of injury or damage to a person's clothes when ascending or descending from the stand.

An additional object is to provide foot- 15 rests for shoe shining stands, which foot- rests are adjustable in a vertical direction so that they may be raised or lowered as occasion requires.

An additional object is to provide an ad- 20 justable foot-rest for shoe shining stands having means whereby it may be lowered to an unobstructing position at the conclusion of the shoe shining operation whereby it will be out of the way of the customer 25 descending from the stand.

A further object of the invention is to 30 provide a device of the above character that is simple in construction, strong and durable, and which it is believed may be manu- factured at a reasonably low cost.

Various other objects and advantages of 35 the invention will become apparent during the continuance of the following descrip- tion.

In the drawings:—

Figure 1 illustrates a section of a shoe 40 shining stand, partly broken away to show the manner of applying the invention thereto.

Figure 2 is a vertical cross section thereof taken on line 2—2 of Figure 1, and,

Figure 3 is a similar section taken on line 3—3 of Figure 1.

In the drawings, 10 indicates the base or 45 platform of a shoe shining stand upon which the chairs for the customers are usually supported. In applying the invention to the platform, the latter is provided in the top wall with pairs of laterally spaced openings

50 11 respectively arranged in front of each chair C, as shown in Figure 2. These open- ings are adapted to receive a vertical up- right or side arm 12 of a U-shaped frame 13 mounted for adjustment vertically of the 55 supporting platform as illustrated. Each upright is provided at its upper free end

with a suitable foot-rest 14 and extending lengthwise of the uprights from a point below the foot-rests 14 to a point near the lower extremity are a series of notches 15. 60 The notches of both uprights correspond in points of position and size in order that the adjustment of the frame may be uniform. Bolted or otherwise fastened to the under side of the top platform-wall is a bracket 16 65 provided at each end with a depending lug 17. This bracket supports the socket mem- bers 18 which are fastened to the lug at each end of the bracket.

Each bracket comprises a pawl-housing 70 19 having a tubular guide 20 integral therewith extending upwardly through opening 11 as shown in the drawing, the extension being indicated at 21. These guides encircle the uprights 12 which are adjustable 75 through the socket members and serve to steady the movement of the frame during its adjustment. Projecting upwardly and inwardly of each socket member is a parti- tioning wall 22 which serves to space the 80 pawl-housing from the lower end of the guides and on the inner face of the parti- tion is a lug 23 about which is coiled one end of spring 24. The other end of the spring is similarly coiled about lug 25 car- 85 ried at the butt end of pawl 26.

The spring is normally tensioned to ex- 90 pand outwardly against the butt end of the pawl for keeping the fore end normally en- gaged with one of the notches of the upright 90 passing through the guide.

The pawl of each socket member is mount- 95 ed on one end of crank shaft 27, which shaft extends cross wise between the socket mem- bers and has its opposite ends journaled in the side walls of each socket casing as shown in Figure 1. At its center, the shaft is pro- 100 vided with a crank 28 to which is suitably clamped, as indicated at 29, one end of a pedal shank 30. This shank has its lower end bent to extend angularly therefrom and pro- jecting outwardly through opening 31 in the front wall of the platform to provide a foot 105 pedal 32 to permit of operating the device from the outside of the platform.

As shown in the several views of the draw- 110 ing, the frame, sockets and operating cranks, etc., are all concealed from view within the interior of the hollow platform and hence present no unsightly projections or danger- ously protruding parts.

In the operation of the device, locking

pawls 26 are normally disengaged from the notches of the uprights by depressing pedal 32 which rotates the crank shaft sufficiently to withdraw the pawl to releasing position. 5 The foot-rests may then be manually adjusted to the proper height by grasping either one or both of the uprights and raising the frame vertically the necessary distance.

Upon releasing the foot pedal, spring 24 10 will force the pawl to enter the notches in the uprights and consequently maintain the same in elevated position. As is obvious the adjustment of the frame may be accomplished without requiring the depression of pedal 32 as the pawls will rise easily over the notched portions of the uprights when the frame is simply raised up. To lower the frame, pedal 32 is merely depressed causing pawl 26 to be brought to releasing position 15 as above described, subsequent to which the weight of the frame will cause the latter to drop downwardly through the guides of the socket members until the foot-rests 14 engage the top of the guide. To avoid breakage of parts and to lessen the impact between the foot-rests and guides, cushioning means in the form of rubber or other elastic caps 33 are provided and arranged upon the top of the guides as shown in the drawings. 20 These caps serve as bumpers for receiving the impact of the foot-rests 14 and serve to lessen the shock or jar of the falling frame.

From the foregoing it is believed that the

advantages and novel features of the invention will be readily understood and therefore further detailed description is deemed unnecessary. 35

What is claimed is:—

1. A shoe shining stand including a supporting platform, a foot-rest frame mounted 40 for vertical adjustment through said platform, said frame including a pair of notched arms, socket members supported interiorly of said platform and providing guide means for the said arms, a crank shaft having its opposite ends journaled in the said socket members, a pawl at each end of the shaft and movable therewith, resilient means normally holding the pawls in engagement with the notched arms, and pedal means for moving 45 the shaft to release the pawls.

2. A shoe shining stand having a platform, a vertically movable U-shaped frame below the platform and having its arms extended through guide openings in the platform, said arms presenting foot-rests at their upper exposed ends, supporting means having engagement with the said arms below the platform for supporting the frame in raised position, and means for releasing the 55 said supporting means to permit the descent of the said frame, said releasing means being operable from a point exteriorly of the said stand.

In testimony whereof I affix my signature. 60

JAMES EMORY WALKER. 65
